IMMERSIBLE ELECTRIC MOTOR

Eustace S. Dunn, Piedmont, Calif., assignor to The Louis Allis Company, Milwaukee, Wis., a corporation of Wisconsin

Application August 6, 1958, Serial No. 52,071

Term of patent 14 years

(Cl. D26—5)

Fig. 1.

Fig. 2.

Figure 1 is a perspective view of an immersible electric motor embodying my new design; and

Figure 2 is a plan view thereof.

The design for the immersible electric motor disclosed is characterized by the oppositely disposed handles in association with the angularly spaced ribs which collectively define the well in the top center and extend uninterruptedly from this well down the sides to the base, all as shown in solid lines in the drawing.

I claim:

The ornamental design for an immersible electric motor, as shown and described.
